20,791. CARPET. *Henry W. Parton*, Yonkers, N. Y., assignor to *The Alex. Smith & Sons Carpet Company*, same place. Application filed April 30, 1891. Serial No. 391,146. Term of patent 3½ years.

UNITED STATES PATENT OFFICE.

HENRY W. PARTON, OF YONKERS, NEW YORK, ASSIGNOR TO THE ALEX. SMITH & SONS CARPET COMPANY, OF SAME PLACE.

DESIGN FOR A CARPET.

SPECIFICATION forming part of Design No. 20,791, dated June 2, 1891.

Application filed April 30, 1891. Serial No. 391,146. Term of patent 3½ years.

To all whom it may concern:

Be it known that I, HENRY W. PARTON, a citizen of the United States, residing at Yonkers, Westchester county, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

My design consists of the body A and border B. The body A consists of a somewhat shaded panel surrounded by intertwining flower, leaf, and branch forms upon a shaded

ground. The border B consists of a somewhat shaded panel surrounded by intertwining flower, leaf, and branch forms upon a shaded ground and of an inner and an outer margin.

What I claim, and desire to secure by Letters Patent, is—

1. A design for carpets, consisting of the body A, substantially as shown.
2. A design for carpets, consisting of the border B, substantially as shown.
3. A design for carpets, consisting of the body A and the border B, substantially as shown.

HENRY W. PARTON.
